Glennir, Way of Lowell, Mass.

Assignor to

The Lowell Manufacturing Company.

Letter Patent No. 1546, dated Feb. 25, 1862.

The schedule referred to in these Letters Patent and making part of the same.

Illustration of my design:

Be it known that of Glennir, Way, of Lowell, in the County of Middlesex and State of Massachusetts, have originated and designed a new Pattern for Carpets or other fabrics, of which the following is a full, clear and exact description, reference being had to the accompanying drawings, making part of this specification.

The design consists of series of figures enclosed by a chain of blocks B. in such a manner as to form two large diamonds A. The spaces between the diamonds are occupied by outline figures similar to those contained in the diamonds.

The colors employed for the different portions of the design may be varied to suit the taste and wish of the manufacturer.

Claim.

What I claim as my invention and desire to secure by Letters Patent, is the design or pattern, for Carpets or other fabrics, herein set forth.
